(57) **CLAIM**

The ornamental design for a test strip holder, as shown and described.

DESCRIPTION

FIG. 1 is a perspective view of a test strip holder with the back side being covered by a back side cover;

FIG. 2 is a bottom view thereof;

FIG. 3 is a top view thereof;

FIG. 4 is a right view thereof;

FIG. 5 is a left view thereof;

FIG. 6 is a back view thereof;

FIG. 7 is a front view thereof;

FIG. 8 is a perspective view of the test strip holder with the back side not being covered by the back side cover;

FIG. 9 is a bottom view thereof;

FIG. 10 is a top view thereof;

FIG. 11 is a right view thereof;

FIG. 12 is a left view thereof;

FIG. 13 is a back view thereof; and,

FIG. 14 is a front view thereof.

The broken lines depict portions of the test strip holder that form no part of the claimed design.

1 Claim, 14 Drawing Sheets
